DESIGN FOR A BROOCH OR SIMILAR ARTICLE

Bertha J. Hansen, Rutherford, N. J.

Application August 12, 1942, Serial No. 107,888

Term of patent 3½ years

To all whom it may concern:

Be it known that I, Bertha J. Hansen, a citizen of the United States, residing at Rutherford, in the county of Bergen and State of New Jersey, have invented a new, original, and ornamental Design for a Brooch or Similar Article, of which the following is a specification, reference being had to the accompanying drawing, forming a part thereof.

In the drawing:

Fig. 1 is a plan view of a brooch or similar article, showing my new design.

Fig. 2 is a side elevational view of the same.

I claim:

The ornamental design for a brooch or similar article, as shown.

BERTHA J. HANSEN.
